COAT

Joseph Siegel, New York, N. Y.

Application July 17, 1936, Serial No. 91,028

11 Claims.

(Cl. 2—97)

My present invention is concerned with improvements in coats of the type which are provided with removable interlinings.

It has heretofore been proposed, notably in several of my pending applications to provide an overcoat or other outer garment having a detachable interlining which is connected to the coat body by an endless line or by interrupted lines of slide-fastener-operated metallic seams. 10 In accordance with prior constructions employing either ordinary interlinings or interlining garments of the type suggested by my pending applications Serial Nos. 73,608 and 83,823, filed respectively April 10, 1936 and June 6, 1936, no 15 altogether satisfactory means has been provided for effectively concealing the slide fastener or zipper teeth.

While protective flaps have been provided, cooperating with the coat body to define channels for receiving the zipper carrying strips of the coats, the flaps themselves come open or blow open when the coat is worn unbuttoned and the zipper teeth are disclosed. The average male citizen, essentially conservative in his tastes 25 appreciates the advantages of the zipper type removable interlining but objects strenuously to anything which detracts from the wholly conventional appearance of the garment, such for instance as the casual exposure of the "zipper" teeth.

By my present invention I entirely overcome this difficulty and provide means independent of the channel-forming flap for concealing and protecting the zipper strip or strips which are carried by the coat body.

I accomplish this result without in any way impairing the ease and facility with which the lining may be applied and with but negligibly increasing the cost of manufacture without adding visibly to the bulkiness of the garment and in such a fashion that the possibility of the zipper being seen, whether the coat is worn with or without the interlining, is reduced to a minimum.

Other objects of the invention will be more 45 fully apparent from the following description in connection with the accompanying drawing wherein:

Fig. 1 is a perspective view of the inside of an overcoat equipped with my removable interlining and embodying the present invention,

Fig. 2 is a view looking at the inner facing of the coat with parts of the various laminations broken away for the sake of clearness,

Fig. 3 is a considerably enlarged broken trans-

verse sectional view on the line 3—3 of Fig. 2, and

Fig. 4 is a view generally similar to Fig. 3 but with the interlining removed.

Referring with more particularity to the drawing, I have used the reference numeral 10 to designate the body of an overcoat, which both internally and externally is entirely conventional in appearance. The inwardly turned facing 11 of the coat, or rather the inner portion of such 10 facing is free of direct connection with the coat body whereby a flap 12 is provided, this flap cooperating with the coat body to define a channel 13. This channel in the form of the invention illustrated follows the inner edge of the facing from one lower corner of the coat around the collar thereof and down to the opposite lower corner.

As above suggested, however, this channel may be continuous or not depending whether the 20 interlining is of more or less standard type, or whether it is constructed in accordance with the teachings of my above copending application Serial No. 83,823.

The channel 13, cooperatively defined by the 25 coat body 10 and the flap 12 of the coat facing 11 is preferably provided with a lining 14. A strip 15 of fabric is folded longitudinally upon itself to provide a pair of sections 16 and 17, section 16 being of slightly greater width than 30 section 17, and both edges of the strip 15 being beaded or piped or enclosing a cord, such as the cords 18 to provide rounded, longitudinally extending beads or ribs of substantially greater thickness than the fabric which they edge.

The folded strip 15 lies within the channel 13 and is sewed directly to the flap-forming portion 12 of the facing 11. This folded strip follows the entire length of channel 13 and between the two sections of the folded strip there is disposed a 40 strip of fabric 19 which carries at one edge a set of metallic teeth 20, adapted to be interlocked with a complementary set of teeth 21 on the interlining 22 to complete a metallic seam of the well-known "zipper" type.

The strip 19 is sewed to sections 16 and 17 of the strip 15 by a continuous line of stitching 23, strip 19 being so deeply inserted between the sections 16 and 17 which embrace it that it terminates well short of the beaded or rounded edges 45 18, 19 of such sections.

While other expedients may be resorted to, I 1 preferably sew the folded-over strip 15 with the zipper-carrying strip sewed in place within it directly to the flap-forming portion 12 of the

facing 11 by two continuous lines of stitching 24 and 25, disposed respectively inwardly and outwardly of the line of stitching 23 which connects strips 15 and 19.

5 The interlining 22 is secured to the coat 10 by actuating a standard slide fastener 26 to interlock the complementary sets of "zipper" teeth 20 and 21. When the lining is in place and these sets of teeth are interlocked they are completely concealed by the beaded edge 18 of strip 17.

In fact this beaded edge completely covers the fabric strip 27 which projects from the edge of the interlining 22 and carries teeth 21. The interlining itself is substantially thicker than strip 27 and lies substantially in edge to edge abutment with the strip 17 as best seen in Fig. 3.

When the interlining is removed, strips 16 and 17 cooperate to conceal the zipper teeth 20. The beaded edge 18 of strip 16 partially or completely overlaps the beaded edge 18 of the strip 17 and the teeth 20 are completely hidden from view.

The interlining 22 requires no special description. In the form illustrated it is sleeveless. Teeth 21 follow all the edges of the lining except the lower edge thereof. A partial silk lining or facing 28 may be employed at the inside of the interlining 22 supplementing a similar lining in the overcoat body proper so that the coat will appear of entirely conventional appearance with or without the interlining in place.

It is altogether in the spirit of the invention to construct the interlining in the form of a separate removable garment, such as for instance, 35 the bath robe shown in my application Serial No. 73,608, the rain coat illustrated in my application Serial No. 83,823 or in the form of a vest or other type of garment.

Particular attention is called to the arrangement and function of the section 17 of the strip 15 and particularly to the beaded, rounded, or otherwise enlarged edge 18 thereof. Strip 17 even independently of strip 16 affords a highly effective concealing means for the teeth 20 and 21 45 regardless of whether strip 16 is employed or not. The latter serves primarily as a supplemental concealing means when the interlining is removed. When it is advantageous to use strip 16 it may be omitted if desired.

50 As above suggested the average citizen has a repugnance for clothes of freakish or unconventional appearance, and while the flap 12 would serve to conceal the separate teeth, under ordinary circumstances it does not provide a fool-proof guard or concealment for them. On windy days, for instance, when the overcoat is worn open, the wind may tend to blow back flap 12 and expose the gleaming metal of the seam. There is less chance of this when the interlining 55 is in place, but when the interlining is removed the flap-forming portion of the facing does blow back. In such an event the teeth 20 are still completely concealed by the overlapping beaded edges 18, 18 of the sections 16 and 17. The use 60 of these beaded or piped or otherwise rounded edges does not cause any appearance of bulginess in the region of the facing because of the two beaded edges completely or partially overlapping as illustrated in Fig. 4 and their combined thickness exceeds but by little the thickness of the 65 teeth themselves.

Another feature of the use of the strip 15 is the fact that it takes much of the strain off of the standard zipper carrying strip 19 which is 70 not of particularly tough material, and further-

more, to all intents and purposes conceals this zipper carrying strip. Likewise the folded protective strip 15 may be made of material approximating in quality and texture the high grade material used to form the lining 14.

Obviously various changes and alterations may be made in the exact arrangement and construction of the parts described without departing from the invention, and hence I consider myself at liberty to make all changes and alterations which fairly fall within the spirit and scope of the appended claims.

Having thus described my invention, what I claim as new and desire to secure by Letters Patent is:

1. An overcoat of the type to removably receive an interlining and be detachably connected thereto by a metallic seam, said coat including an inwardly turned facing the free inner edge of which constitutes a flap which cooperates with the coat body to provide an inwardly facing channel, a tooth carrying strip arranged within the channel and a protective concealing strip lying between the channel flap and the toothed strip and terminating short of the edge of the flap but completely covering the toothed strip.

2. An overcoat of the type to removably receive an interlining and be detachably connected thereto by a metallic seam, said coat including an inwardly turned facing the free inner edge of which constitutes a flap which cooperates with the coat body to provide an inwardly facing channel, a tooth carrying strip arranged within the channel and a protective concealing strip lying between the channel flap and the toothed strip and terminating short of the edge of the flap but completely covering the toothed strip, said protective strip having a beaded edge to conceal the teeth.

3. An overcoat of the type to removably receive an interlining and be detachably connected thereto by a metallic seam, said coat including an inwardly turned facing the free inner edge of which constitutes a flap which cooperates with the coat body to provide an inwardly facing channel, a tooth carrying strip arranged within the channel and a protective concealing strip lying between the channel flap and the toothed strip and terminating short of the edge of the flap but completely covering the toothed strip, said protective strip having a beaded edge to conceal the teeth of the toothed strip and of a complementary strip adapted to be carried by the interlining.

4. An overcoat of the type to removably receive an interlining and be detachably connected thereto by a metallic seam, said coat including an inwardly turned facing the free inner edge of which constitutes a flap which cooperates with the coat body to provide an inwardly facing channel, a tooth carrying strip arranged within the channel and a protective concealing strip lying between the channel flap and the toothed strip and terminating short of the edge of the flap but completely covering the toothed strip, said protective strip having a beaded edge to conceal the teeth, a second beaded protective strip lying within the channel between the toothed strip and the coat body.

5. An overcoat of the type to removably receive an interlining and be detachably connected thereto by a metallic seam, said coat including an inwardly turned facing the free inner edge of which constitutes a flap which cooperates with the coat body to provide an inwardly facing

- channel, a tooth carrying strip arranged within the channel and a protective concealing strip lying between the channel flap and the toothed strip and terminating short of the edge of the flap but completely covering the toothed strip, said protective strip having a beaded edge to conceal the teeth, a second beaded protective strip lying within the channel between the toothed strip and the coat body and having its beaded edge slightly out of registration with the beaded edge of the first mentioned concealing strip whereby the beaded edges at least partially overlap when no interlining is in place, said two protective strips being formed by a longitudinally folded single strip having beaded edges, and the tooth carrying strip being sewed to both protective strips and the latter being sewed to each other and to the channel flap. 5
6. An overcoat of the type to removably receive an interlining and be detachably connected thereto by a metallic seam, said coat including an inwardly turned facing the free inner edge of which constitutes a flap which cooperates with the coat body to provide an inwardly facing channel, a tooth carrying strip arranged within the channel and a protective concealing strip lying between the channel flap and the toothed strip and terminating short of the edge of the flap but completely covering the toothed strip, 10 said protective strip having a beaded edge to conceal the teeth, a second beaded protective strip lying within the channel between the toothed strip and the coat body and having its beaded edge slightly out of registration with the beaded edge of the first mentioned concealing strip whereby the beaded edges at least partially overlap when no interlining is in place. 15
7. An overcoat of the type to removably receive an interlining and be detachably connected thereto by a metallic seam, said coat including an inwardly turned facing the free inner edge of which constitutes a flap which cooperates with the coat body to provide an inwardly facing channel, a tooth carrying strip arranged within the channel and a protective concealing strip lying between the channel flap and the toothed strip and terminating short of the edge of the flap but completely covering the toothed strip, 20 said protective strip having a beaded edge to conceal the teeth of the toothed strip and of a complementary strip adapted to be carried by the interlining and to abut with the interlining material which carries the second toothed strip. 25
8. An overcoat of the type to removably receive an interlining and be detachably connected thereto by a metallic seam, said coat including an inwardly turned facing the free inner edge of which constitutes a flap which cooperates with the coat body to provide an inwardly facing channel, a tooth carrying strip arranged within the channel and a protective concealing strip lying between the channel flap and the toothed strip and terminating short of the edge of the flap but completely covering the toothed strip, 30 said protective strip having a beaded edge to conceal the teeth, a second beaded protective strip lying within the channel between the toothed strip and the coat body, an interlining having a tooth carrying strip projecting from the edge thereof, said strip being concealed by the first mentioned protective strip. 35
9. An overcoat of the type to removably receive an interlining and be detachably connected thereto by a metallic seam, said coat including an inwardly turned facing the free inner edge of which constitutes a flap which cooperates with the coat body to provide an inwardly facing channel, a tooth carrying strip arranged within the channel and a protective concealing strip lying between the channel flap and the toothed strip and terminating short of the edge of the flap but completely covering the toothed strip, 40 said protective strip having a beaded edge to conceal the teeth, a second beaded protective strip lying within the channel between the toothed strip and the coat body, an interlining having a tooth carrying strip projecting from the edge thereof, said strip being concealed by the first mentioned protective strip. 45
10. An overcoat of the type to removably receive an interlining and be detachably connected thereto by a metallic seam, said coat including an inwardly turned facing the free inner edge of which constitutes a flap which cooperates with the coat body to provide an inwardly facing channel, a tooth carrying strip arranged within the channel and a protective concealing strip lying between the channel flap and the toothed strip and terminating short of the edge of the flap but completely covering the toothed strip, 50 said protective strip having a beaded edge to conceal the teeth, a second beaded protective strip lying within the channel between the toothed strip and the coat body, an interlining having a tooth carrying strip projecting from the edge thereof, said strip being concealed by the outer protective strip and the interlining proper having edge 55 to edge abutment with the first mentioned protective strip when in place within the coat. 60
